STOP-MOTION MECHANISM.

1,151,534.

Specification of Letters Patent. Patented Aug. 24, 1915.

Application filed July 21, 1911. Serial No. 639,746.

To all whom it may concern:

Be it known that I, ALFRED R. WOOD, a citizen of the United States, residing at Mamaroneck, in the county of Westchester 5 and State of New York, have invented certain new and useful Improvements in Stop-Motion Mechanisms, of which the following is a specification, reference being had thereto in the accompanying drawings.

10 This invention relates to an improvement in stop-motion mechanisms, and more particularly to mechanisms of that class designed for control of the stitch-forming and feeding devices of sewing machines for the 15 production of groups of stitches of predetermined number, as in the stitching of button-holes and in barring and tacking.

The invention has for its primary object to increase the certainty and precision of 20 action of this class of mechanism.

In the preferred form of the improvement, the rotary shaft to be controlled has fixed thereon a stopping-cam formed with an operative face inclined to its direction of 25 movement and terminating in an inwardly extending shoulder, and also provided with a second shoulder disposed in a different plane.

A laterally swinging stop-lever mounted 30 upon a fixed fulcrum carries a longitudinal spring-pressed endwise-movable plunger adapted to engage the operative face of said cam and the adjacent shoulder and also a transverse spring-pressed plunger adapted 35 to engage the second-named shoulder of the cam. The said shaft has fixed thereon a brake-wheel embraced by a friction-band adapted to be tightened upon the brake-wheel by a connection with the longitudinal 40 spring-pressed plunger under the action of the operative face of said cam but to be slackened when such plunger passes the adjacent shoulder subsequently to the engagement of the second-named shoulder with the 45 transverse plunger by which the shaft is brought to rest.

A spring serves to normally press the stop-lever into active position wherein said plungers are brought into operative relation 50 with the stopping-cam, and the stop-lever is provided with a lateral arm connected with a reciprocating operating rod formed with two oppositely presented shoulders adapted for engagement respectively by a 55 primary detent-lever and a secondary de-

tent-lever movable independently thereof. The primary detent-lever is actuated to release the operating rod by engagement with a tripping stud upon a feed-cam or other operative part of the machine, while the operating rod carries a tripping device for the auxiliary detent-lever to which is attached a treadle connection in such manner that the actuation of the treadle causes first the disengagement of the auxiliary detent-lever 60 from the operating rod and then the drawing down of the operating rod to shift the stop-lever laterally for disengagement of its independent plungers from the stopping-cam to set the machine in motion. 65

The invention will be understood more fully by reference to the accompanying drawings, in which—

Figure 1 is a rear side elevation of a portion of a buttonhole stitching machine provided with the present improvements, and Fig. 2 a plan of the same. Fig. 3 is a rear end view of the machine, Fig. 4 an elevation of the stop-motion mechanism viewed from the front end, and Fig. 5 a sectional side elevation of the rear end of the machine and the stop-motion. Fig. 6 is a detail view of the stopping cam and adjacent portions of the angularly arranged plungers in stopping position. Fig. 7 is a detail view of the lower portion of the operating rod with the tripping member carried thereby. Figs. 8 and 9 are respectively an edge view and a bottom plan of the operating rod and the means for locking the same in its two extreme positions. 75

The present improvement is shown embodied in a stop-motion mechanism similar in general construction to that forming the subject of the United States patent to H. W. 80 Slater and J. T. Hogan, No. 894,073, dated July 21, 1908. The sewing machine frame is shown constructed with the bed-plate 1 and the bracket-arm comprising the hollow standard 2 and the tubular member 3, the standard 2 having the bearing boss 4 containing the bushing 5 in which is journaled the rearward end of the main or driving shaft 6 of the machine carrying the fast and loose pulleys 7 and 8, respectively. 85

Secured upon the driving shaft intermediate the boss 4 and the fixed pulley 7 is the stopping-cam comprising the rigidly connected disks 9 and 10, the former having a substantially snail-shaped periphery 11 ter- 90

minating in its outer portion in the inwardly extending shoulder 12 forming a step connecting the inner and outer operative portions of the periphery. The disk 10 5 is shown provided with a lateral projection 13 having a facing afforded by the forward edge of a hardened block 14 let into a lateral recess in said disk and secured therein by means of a fastening screw 15, the forward 10 edge of the block 14 providing a stopping shoulder by means of which the shaft is finally brought to rest.

The rearward end of the standard 2 is formed with a seat 16 upon which is secured 15 by means of the bolt 17 the foot 18 of a bracket formed with spaced lugs 19 carrying the alined center screws 20 upon which is journaled the swinging stop-lever 21. The stop-lever is formed with the split bearing 20 boss 22 entered by the externally threaded bushing 23 which forms one of the bearings of the endwise reciprocating plunger 24 whose upper portion is journaled in the bearing member 25 of the stop-lever and 25 whose upper extremity is adapted to engage the periphery of the stopping-cam disk 9. The plunger 24 is normally pressed upward into operative engagement with the stopping cam by means of the spring 26 interposed between the inner ends of the bushing 23 and the collar 27 adjustably secured upon said plunger within the central aperture 21* of the stop-lever by means of the set-screw 28 and provided with the rearwardly extending lug 29.

At its rearward edge, the stop-lever is formed with a transverse socket 30 entered by the externally threaded bushing 31 which affords one of the bearings for the reduced 40 rearward portion 32 of a transverse plunger-bar whose other end portion 33 is mounted within a bearing 34, and is provided with an upwardly extending lug 35 affording an abrupt shoulder 36 adapted for engagement 45 with the shoulder 14 of the stopping-cam. The reduced portion 32 of the momentum-absorbing plunger is embraced by the buffer-spring 37 interposed between the inner end of the bushing 31 and the collar 33* of 50 said plunger, and it is retained yieldingly in normal position upon the stop-lever by means of a second spring 38 which is interposed between the outer extremity or head of the bushing 31 and the adjustable thrust-nut 39 applied to the threaded outer extremity of the plunger and secured in position by means of the lock-nut 40.

Fixed upon the driving shaft 6, and preferably formed integral with the stopping-cam, is the brake-wheel 41 surrounded by the brake-strap 42 which is shown provided with a facing 43 of soft material such as rawhide, and having one end secured by means of screws 44 upon the lug 45 formed 65 upon one of the ears 19 of the stop-lever

supporting bracket. The opposite end of the brake-strap is attached to a pull-rod 46 threaded to receive the thrust-nut 47 with the lock-nut 48 and the thrust-nut 49 with thumb-nut 50.

Fulcrumed upon the stud-screw 51 tapped into the lug of the bracket to which one end of the brake-band is attached is a lever 52 extending transversely beneath the lug 29 carried by the plunger 24 and apertured at its opposite end to receive the pull-rod 46. The outer end of the lever 52 is maintained yieldingly in contact with the thrust-nut 47 by means of a spring 53 interposed between the same and the thrust-nut 49 which latter is adjustable upon the pull-rod for varying the tension of the spring. As will be observed, the descent of the plunger-bar 24 under the action of the cam edge 11 operates through the engagement of the lug 29 with the lever 52 to draw downwardly the free end of the brake-band so as to produce an additional resistance to arrest the driving shaft in addition to that imposed by the engagement of the plunger-bar 24 upon the cam-disk 9.

The bushing 23 carries a loose washer 54 having a perforation entered by one end of a spring 55 whose other end enters a transverse aperture in a pin 56 depending from the bed-plate, by means of which the stop-lever is normally drawn into upright position upon its center-screws 20 so as to bring its longitudinal and transverse plunger-rods into operative relation with their respective portions of the stopping-cam. The upper transverse member of the stop-lever has secured thereto by means of the screws 57 the foot 58 of a forwardly extending arm 59 to which is secured by means of screws 60 the shank 61 of the belt-shipper 62 adapted to register with the fast and loose pulleys respectively when the stop-lever is in retracted and stopping position.

The forward end of the arm 59 is formed with a slot 63 entered by the cross-pin 64 in the forked upper end 65 of the operating rod 66 journaled in an aperture in the bed-plate through which it extends. The rod 66 has secured thereon beneath the bed-plate by means of the set-screw 67 the collar 68 shown formed with a flat upper face 69 and with its lower end provided with a notch 70 at one side of the rod 66. The upper face 69 and the notch 70 in the lower face afford oppositely presented shoulders for engagement with the detent-levers by which the rod is locked in upper and lower position, respectively.

Upon the fulcrum-screw 71 depending from the bed-plate is journaled the hub 72 of the main detent-lever having a rearwardly extending arm 73 adapted for engagement with the upper face 69 of the collar 68 and a forwardly projecting arm 74 upon which is 125 130

adjustably secured by means of screws 75 the plate 76 formed with the laterally projecting nose 77 normally lying within the path of movement of the tripping pin 78 5 projecting from the upper face of the rotary feed-wheel 79. Secured to the outer edge of the arm 74 by means of the screw 80 is the flat spring 81 whose outer portion normally rests in contact with the depending rib 1^x of the bed-plate to normally maintain the nose-piece yieldingly within the path of movement of the tripping pin 78. Overlying the detent lever-arm 73 is the auxiliary detent-lever 82 which is fulcrumed 10 at one end upon the stud-screw 71 with its other end confined within the stirrup 83 secured upon the lever-arm 73 by means of the screws 84. The lever 82 is normally drawn toward the collar 68 by means of the 15 spring 85 attached to the same at one end and at the opposite end to the bed-plate rib 1^x, and is adapted to enter the notch 70 in said collar whose inner wall affords a stop therefor.

20 The flattened lower end 66^x of the rod 66 is formed with a transverse aperture entered by and serving as a bearing for the axial stud 86 of the segmental tripping cam-disk 87 formed upon one side with the wedge-shaped cam portion 88 adapted to engage the beveled edge 82^x of the auxiliary detent-lever 82. The cam-disk 87 is provided opposite the operative portion 88 and near the periphery with the aperture 89 in which 25 is hooked the upper end of the chain 90 or other connection with a treadle or knee-lever by which the stop-motion is initially actuated. The cam-disk 87 is provided with an eye 91 entered by one end of the spring 92 30 whose opposite end embraces the set-screw 67, whereby the disk is normally maintained with its cam portion 88 retracted from the detent-lever 82 and the connection with the chain 90 arranged at one side of the pivotal 35 stud 86. The operating rod 66 has secured thereto above the bed-plate by means of the set-screw 93 the stop-collar 94 whose engagement with the upper face of the bed-plate serves to limit the downward movement of the rod 66 and the forward retracted 40 movement of the stop-lever whose movement in the opposite direction under the action of its spring 55 is arrested by means of the stud 95 secured in position by means of 45 the jam-nut 96.

50 When the machine is at rest, the stop-lever is in its rearward retracted position as represented in Fig. 1, the upper end of the plunger-bar 24 having dropped off the high point of the peripheral cam 11 behind the shoulder 12 and the striking member 14 of the stopping cam resting in engagement with the shoulder 36 of the transverse plunger-bar, as represented in Fig. 6. At this 55 time, the operating rod 66 is in its upper

position and the auxiliary detent-lever 82 is in engagement with the operative face of the notch 70 in the collar 68, as represented in Figs. 1, 3 and 8, the tripping cam-disk 87 being maintained in retracted or inoperative 60 position by means of the spring 92. The drawing down of the treadle connection 90 causes an initial quarter-turn of the tripping cam-disk 87 for engagement of the operative cam portion 88 with the adjacent 65 edge of the auxiliary detent-lever 82 which latter is pressed backwardly in opposition to its spring 85, and after such release of the collar 68 the continued drawing down of said connection causes the descent of the 70 rod 66 and the tilting of the stop-lever into its forward or retracted position, thereby disengaging its plunger-bars from the stopping cam and throwing the belt-shipper to carry the driving belt from the loose to the 75 fast pulley. As the collar 68 reaches its lowest position, the primary detent-lever snaps over the same and locks it therein. The machine now continues its operation until the feed-cam 79 has nearly completed a rotation, 80 when its tripping pin 78 engages the nose 77 of the primary detent-lever and rocks the same in opposition to its spring 81 to disengage the arm 73 from the collar 68, thereby permitting it to rise under the action of 85 the stop-lever spring 55 by means of which the stop-lever is thrown backwardly into stopping position with the operative portions of its plunger-bars disposed within the paths of movement of the component 90 disks 9 and 10 of the stopping-cam, the belt-shipper being simultaneously shifted to throw the driving belt from the fast to the loose pulley.

95 As the machine continues to run under its 100 momentum, the upper end of the longitudinal plunger-bar 24 rides up the eccentric operative edge of the cam-disk 9 which continues to thrust it downwardly and under the engagement of the lug 29 with the lever 52 105 to compress the brake-spring 53, thereby yieldingly drawing down the adjacent end of the brake-band and applying with increasing intensity a frictional drag upon the brake-wheel 41. When the stopping-cam reaches a position wherein the shoulder 12 is above the plunger-bar 24, as represented in Figs. 1 to 5 inclusive, the striking block 14 engages the shoulder 36 of the 110 momentum-absorbing plunger, the shock of such engagement in overcoming the remaining momentum being taken up by the spring 37. As the cam-shoulder 12 passes the upper extremity of the plunger-bar 24, the latter snaps behind the same and serves as a 115 stop to prevent the recoil of the stopping-cam and the main-shaft under the action of the spring 37. As the plunger-bar 24 rises behind the cam-shoulder 12, the pressure of 120 the brake-spring 53 is relieved and the ac-

tion of the brake ceases; but the operation of the parts is so timed that the parts 14 and 35 are brought into forcible engagement before the rise of the plunger-bar 24, so that 5 no interval exists between the removal of the frictional drag upon the main-shaft and the operation of the cushion-spring 37 in absorbing the remaining momentum of the machine communicated through the stop- 10 ping-cam. Thus, the operation of the different successively acting members in absorbing the momentum of the machine is continuous and thereby insures against the noisy operation of the stop-motion and the injury 15 of the interengaging parts through the intensity of their impact, which has been a serious defect of certain other constructions. The adjusting means for the brake obviously affords provision for reducing the momentum 20 to the required extent for a given speed of rotation of the shaft before the final action of the transverse plunger-bar.

By timing the parts to effect the engagement of the striking block 14 with the shoulder 36 of the momentum-absorbing plunger while the shoulder 12 of the cam-disk 9 is still above the end of the upright plunger 24, as represented in Fig. 4, the plunger 24 is not permitted to rise for engagement with 25 the shoulder 12 until the buffer-spring 37 has been materially compressed in absorbing the remaining momentum of the mechanism, so that when the machine comes to rest the stopping cam is held securely against 30 the shoulder 12 until the buffer-spring 37 has been materially compressed in absorbing the remaining momentum of the mechanism, so that when the machine comes to rest the stopping cam is held securely against 35 turning in either direction by engagement of the members 14 and 35 and the cam-shoulder 12 against the side of the plunger 24.

In throwing the stop-lever for starting the machine, before the plungers are wholly 40 retracted from operative relation with the stopping-cam the belt-shipper has drawn the driving belt from the loose pulley partially over upon the tight pulley so as to produce a tendency to turn the main-shaft in opposition to the yielding resistance of the buffer-spring 37. Were the latter not under a considerable tension, this would produce the repeated slipping and engagement of the belt upon the fast pulley with a corresponding 45 pounding of the interengaging parts of the stop-motion; but in practice the tension of the springs and adjustment of the various parts is such that the then compressed spring 37 serves to resist the imperfect action of 50 the belt to induce the rotation of the tight pulley until the interengaging parts of the stop-motion are wholly disengaged, when the operation of the machine is permitted to 55 proceed.

60 It has long been common heretofore, in connection with machines for producing groups of stitches of predetermined number, to provide means for locking the stop-motion in retracted position during the performance of a cycle of operation of the 65

mechanism, such locking means being disengaged by the action of a cycle-cam to permit its action in arresting the mechanism. In machines in which the motion-arresting member of the stopping mechanism is 70 thrown by means of a spring into the path of operation of a rapidly moving part to be acted upon thereby, it frequently happens that continued wear or the chipping of the edges of such parts by continued use produces a tendency to force the spring-pressed part backwardly in opposition to its actuating spring so as to render the stop-motion 75 ineffective and produce a liability of breakage. 80

According to the present improvement, the stop-lever is not only provided with the customary locking means for maintaining it in retracted position during the normal operation of the machine, but it also has 85 means whereby, when once thrown into operative or stopping position, it is securely locked in such position so as to insure the proper action of the interengaging rotary and non-rotary parts. 90

In stop-motion mechanisms employing a plurality of endwise movable spring-pressed plungers adapted to be shifted laterally into and out of operative relation with the stopping-cam respectively when 95 stopping and starting the machine, it has been the practice to grind the upper extremity of the initially acting plunger with an incline having its higher edge on the side toward the stopping-cam, so that when said 100 plunger is thrown into operative relation with the latter a corresponding slight incline in the operative face of such cam in the other direction will insure the effective coöperation of the interengaging parts. Under such conditions, the reaction produced by the brake-spring upon the plunger 105 has a tendency to throw the same laterally out of operative relation with the stopping-cam, which causes the operative end of the plunger to become slightly worn. As a result only the forward edge of the striking block carried by the cam engages the shoulder of the transverse plunger, so that the edges of both these members become battered and worn after continued use sufficiently to cause the main-shaft of the machine to make one or more revolutions after the stop-motion has been tripped, and thereby repeatedly thrust the first-named 110 plunger out of operative position to be returned by its laterally acting spring. According to the present improvement, these 115 plungers are both positively locked in operative relation with the stopping-cam promptly upon beginning their motion-arresting operation which is completed without the described premature disarrangement of the operative parts. 120

125 It will be readily understood that the 130

means for locking the motion-arresting member of the stop-motion in operative relation with the rotary member coöperating therewith is not limited to the embodiment herein shown and described nor to association with the stop-motion mechanism represented in the accompanying drawing, as it is susceptible of construction and arrangement in very different forms and associations within the scope of the present invention.

Having thus set forth the nature of the invention, what I claim herein is:—

1. The combination with a driven rotary shaft, of a stop-motion comprising a rotary member mounted upon and movable with said shaft and having a shoulder transverse to its direction of movement, a motion-arresting member adapted to be shifted into and out of operative position for engagement with said shoulder of the rotary member in effecting the starting and stopping of said shaft, and means acting independently of the rotary movements of the shaft for positively locking said motion-arresting member within the range of movement of said shoulder, said means acting automatically when the motion-arresting member is shifted into operative position.

2. The combination with a driven rotary shaft, of a stop-motion comprising a rotary member mounted upon and movable with said shaft, and having a shoulder transverse to its direction of movement, a motion-arresting member adapted to be shifted into and out of operative position for engagement with said shoulder of the rotary member in effecting the starting and stopping of said shaft, means acting automatically and independently of the rotary movements of the shaft for positively locking said motion-arresting member within range of movement of said shoulder, and means for successively rendering ineffective said locking means and shifting the arresting member out of operative relation with said rotary member.

3. A stop-motion comprising a rotary shaft and a stopping cam carried thereby, a laterally movable spring-pressed plunger adapted for operative engagement with said cam, a spring for throwing said plunger laterally into operative relation with the cam, means acting automatically and wholly independently of the rotary movements of the shaft for locking said plunger against lateral movement from both operative and inoperative relation with said cam, automatically acting means for rendering the locking means ineffective while the plunger is in inoperative relation with the cam, and manually controlled means movable independently of the plunger for rendering the locking means ineffective while the plunger is in operative relation with the cam.

4. A stop-motion comprising a rotary shaft and a stopping cam carried thereby, a swinging stop-lever, a spring-pressed plunger carried by said stop-lever, a spring for shifting said stop-lever to carry said plunger into operative relation with the stopping cam, automatically acting means controlled independently of the rotary movement of said main-shaft for locking the stop-lever in extreme positions with said plunger respectively in operative and inoperative relation with the stopping cam, automatically controlling means for unlocking said stop-lever in one of its extreme positions, and manually controlled means for unlocking said lever in its other extreme position.

5. A stop-motion comprising a rotary shaft and a stopping cam carried thereby, a laterally movable spring-pressed plunger adapted for operative engagement with said cam, a spring for shifting said plunger laterally into operative relation with the cam, and a locking device comprising two spring-actuated detent levers movable relatively to each other upon a common pivotal support and adapted to automatically and successively lock said plunger against lateral movement from both operative and inoperative relation with said cam.

6. A stop-motion comprising a rotary stopping-cam, a laterally movable spring-pressed plunger adapted for operative engagement with the same, plunger-shifting means adapted for moving the plunger into and out of operative relation with the stopping-cam and including a reciprocatory element having oppositely presented shoulders, separate detent-levers respectively adapted to engage said shoulders, and means for operating said detent-levers.

7. A stop-motion comprising a rotary stopping-cam, a laterally movable spring-pressed plunger adapted for operative engagement with the same, plunger-shifting means adapted for moving the plunger into and out of operative relation with the stopping-cam and including a reciprocatory element having oppositely presented shoulders, separate detent-levers respectively adapted to engage said shoulders, means connected with said reciprocatory element for retracting one of said levers from engagement with its respective shoulder, and means for retracting the other of said levers from operative relation with said element.

8. A stop-motion comprising a rotary stopping-cam, a laterally movable spring-pressed plunger adapted for operative engagement with the same, plunger-shifting means adapted for moving the plunger into and out of operative relation with the stopping-cam and including a reciprocatory element having oppositely presented shoulders, separate detent-levers respectively adapted

to engage said shoulders, an oscillatory tripping cam pivotally mounted upon and movable with said reciprocatory element and adapted for operative engagement with one 5 of said detent-levers, means independent thereof for retracting the other of said detent-levers, and means connected with said tripping cam for actuating the same to retract the first-named detent-lever and to 10 thereafter act through said reciprocatory element to shift said plunger from one to the other extreme position relative to the stopping-cam.

9. The combination with a rotary driven 15 shaft, of a stopping-cam mounted thereon and movable therewith, a brake device applied to said shaft, a yielding motion-arresting member adapted to engage said stopping-cam for arresting the motion of said 20 shaft, and means connected with and controlled by said motion-arresting member for operating said brake device to apply a frictional drag upon said shaft preparatory to its stoppage and to relieve said frictional 25 drag subsequent to the engagement of said motion-arresting device with the stopping-cam and prior to the final stoppage of the shaft.

10. The combination with a rotary driven 30 shaft, of a rotary member mounted upon and movable with said shaft and formed with a cam surface inclined to its direction of rotation and an adjacent shoulder and with a second shoulder disposed in a different plane from the first-named shoulder, a swinging stop-lever 35 movable transversely of the direction of movement of said cam, a spring-pressed plunger mounted in said stop-lever and adapted to engage the cam surface and the adjacent shoulder of said rotary member, a second spring-pressed plunger mounted upon said stop-lever transverse to the first-named plunger and adapted to engage the second-named shoulder of 40 said rotary member, means for shifting said stop-lever to throw said plungers into and out of operative relation with said rotary member, a brake-strap embracing said brake-wheel, and an operative connection 45 between said longitudinal plunger and the brake-strap, the parts being so arranged and operated that the second-named plunger engages its respective shoulder of said rotary member while the first is still in operative engagement with said cam surface.

member, and a brake device applied to said shaft and having an operative connection with the first-named plunger whereby it is 50 caused to produce a frictional drag upon said shaft while the plunger is in operative relation with said cam surface, the parts being so arranged and operated that the second-named plunger engages its respective shoulder of said rotary member while the first is still in operative engagement with said cam surface. 55

11. The combination with a rotary driven 60 shaft, of a rotary member mounted upon and movable with said shaft and formed with an eccentric peripheral cam surface and an adjacent shoulder and with a second shoulder disposed in a different plane from the first-named shoulder, a brake-wheel fixed upon said shaft, a swinging stop-lever movable transversely of the direction of movement of said cam, a longitudinal spring-pressed plunger mounted in said stop-lever and adapted to engage the cam 70 surface and the adjacent shoulder of said rotary member, a second spring-pressed plunger mounted upon said stop-lever transverse to the first-named plunger and adapted to engage the second-named shoulder of 75 said rotary member, means for shifting said stop-lever to throw said plungers into and out of operative relation with said rotary member, a brake-strap embracing said brake-wheel, and an operative connection 80 between said longitudinal plunger and the brake-strap, the parts being so arranged and operated that the second-named plunger engages its respective shoulder of said rotary member while the first is still in 85 operative engagement with said cam surface.

In testimony whereof, I have signed my name to this specification, in the presence of two subscribing witnesses.

ALFRED R. WOOD.
